UNITED STATES PATENT OFFICE.

WALTER A. SCHMIDT, OF LOS ANGELES, CALIFORNIA, ASSIGNOR TO INTERNATIONAL PRECIPITATION COMPANY, OF LOS ANGELES, CALIFORNIA, A CORPORATION OF CALIFORNIA.

APPARATUS FOR ELECTRICAL PRECIPITATION OF SUSPENDED MATERIAL FROM GASES.

Continuation of application Serial No. 127,606, filed October 25, 1916. This application filed September 14, 1922. Serial No. 538,284.

To all whom it may concern:

Be it known that I, WALTER A. SCHMIDT, a citizen of the United States, residing at Los Angeles, in the county of Los Angeles and State of California, have invented a new and useful Apparatus for Electrical Precipitation of Suspended Material from Gases, of which the following is a specification.

10 This invention relates to apparatus for subjecting gases to electrical action for the purpose of precipitating suspended particles from such gases by electrical action, and the main object of the invention is to provide improved means for dislodging the precipitated material from the parts on which the same is precipitated, so that it may be collected in suitable receptacles.

20 This application is a continuation of my application Serial Number 127,606, filed October 25, 1916, for apparatus for electrical treatment of gases.

The accompanying drawings illustrate embodiments of my invention, and referring thereto:

Fig. 1 is a horizontal section of an apparatus of the tubular electrode type, taken on line 1—1 in Fig. 2.

25 Fig. 2 is a vertical section on line 2—2 in Fig. 1.

Fig. 3 is a vertical section on line 3—3 in Fig. 1.

Fig. 4 is a vertical section of another form of the invention, showing the application 35 of the hammer means to treaters in which the discharge electrodes are formed as fine wires.

Fig. 5 is a vertical section on line 5—5 in Fig. 4.

40 Fig. 6 is a horizontal section on line 6—6 in Fig. 6.

Fig. 7 is a side elevation of the top header shown in Fig. 4.

45 Fig. 8 is a vertical section of one of the hammer devices, the bearing therefor being shown in section.

In Figs. 1 to 3, I have shown my invention applied in connection with a gas treater comprising a plurality of vertical pipes, the 50 invention being, however, applicable to electrical precipitators or treaters of any of the well known types.

The apparatus shown in Figs. 1 to 3 of the drawing comprises a plurality of vertical flues, tubes or pipes 1, connected at or 55 near their lower ends to suitable means for conducting the gases, and at or near their upper ends into a header 6, into which opens a flue for conducting the gas. The invention is applicable in connection with 60 either up draft or down draft through the treater flues 1, the drawing showing a construction more particularly designed for down draft, in which case the flue may be the gas supply flue, which is in connection 65 with a furnace or other source of gas containing suspended particles. The pipe or treater flues 1 open at their lower ends into suitable means, not shown, for conducting away the treated gases.

70 These discharge electrodes 9 are shown as mounted on a frame, supported on insulators 10 in chambers or insulator boxes 11, extending alongside the top header 6, suitable insulating means, such as discs 12 of 75 insulating material, being provided where the main beams 13 of said frame pass through the walls of the header. Said electrodes 9 may be suspended from cross bars 14 supported by the beams 13 and may be 80 rigidly secured to said cross bars. In case the electrodes 9 are of such construction as to make further support necessary, they may be braced or spaced at their lower ends by suitable connecting means. The main 85 beams 13 preferably consist of pipes of sufficient diameter to provide the required rigidity. In order to protect the insulating discs or plates 12 from undue electrical strain by reason of excessive field intensity where the main beams 23 pass 90 through them, I have found it advantageous, in some cases, to provide rounded conductors 18, formed, for example, as discs having enlarged rounded rims of larger curvature than the beams 13, said conductors 95 18 being mounted on said beams at each side of each insulating disc 12 and spaced slightly therefrom.

100 Knocking or hammer devices are provided for the discharge electrodes, said devices consisting, for example, of hammer levers 20, pivotally mounted at 21 on the insulated horizontal support or frame 13, and adapted

to impart a vertical blow to said frame and the electrodes 9 hung therefrom. These hammer levers 20 may be operated by flexible operating means 22, provided with insulators 23, so as to permit of operation of the hammer means 20 without danger to the person operating the same in case he neglects to cut off the current to the apparatus before operating the hammer means for the discharge electrodes.

Suitable means are also provided for knocking or jarring the collecting electrodes; for example, hammer levers 25 carried by shafts 26, which are mounted to rock in bearings 27, and are operated by suitable means outside the treater casing, for example, by chains 28 connected to lever mechanism 29 for operating said shafts, said hammer levers 25 being adapted to strike plates 30 rigidly mounted on and between adjacent flues 1.

Any suitable means may be provided for maintaining the requisite difference of potential between the electrodes above described. Thus, as shown in Fig. 1, the high tension side of a step-up transformer 36 may be connected through a rectifier 31 and a switch 32 to wire 33 leading to the high tension frame 13 of the treater. The collecting electrodes 1 of the treater are preferably grounded as indicated at 34 and the rectifier has a ground connection 35 to complete the circuit.

In the operation of the treater, the gases to be treated for precipitation of suspended material therefrom, are passed through the flues 1 and are then subjected to electrical action so as to effect electrical precipitation of the suspended material on the electrodes 1 and 9. The material deposited on the collecting electrodes may be removed from time to time, by operation of the hammer or knocking devices 25 by their operating means 28, causing sudden vertical jar on the electrodes 1, with the result that the deposited material is loosened and falls directly into suitable receiving means, it being understood that the electrical current will in general be cut off from the apparatus by opening switch 32, at such times of cleaning, to enable the collected material to more freely drop from the electrodes. Similarly such material as is deposited on the discharge electrodes 9 may be dislodged by operation of the hammer or knocking or jarring means 20. This feature of my invention, in regard to jarring of the discharge electrodes, is not limited to the specific form of such electrode shown and described, but may be applied in connection with any of the usual forms of discharge electrodes, whenever there is a tendency to accumulation of precipitated material thereon.

Figs. 4 to 8 illustrate a modification of the invention in which the collecting electrodes

are formed as plates or screens 37, hung from frames or beams 38 in a chamber 39 and the discharge electrodes are formed as wires 40 suspended from bars 41 which extend horizontally between and are fastened to horizontal frame members 42 formed, for example, as pipes, which extend through insulating discs 43, in the walls of chamber 39 and are supported on insulators 44 outside of said chamber. Chamber 39 communicates at its lower end with a chamber or flue 45 for conducting the gas thereto, and at its upper end with a stack or outlet flue 46. Suitable tensioning weights 47 and spacing frame 48 may be provided at the lower ends of wires 40. The knocker means for the discharge electrodes consists of arms 50 extending over the respective horizontal supporting bars 41 and mounted, for example, on shafts 51 extending axially within the respective supporting pipes 42 and provided with arms 52 whereby they may be operated by suitable operating means such as a chain 54 provided with an insulator 53. In operating these knocking means the hammer levers or arm 50 are lifted by the operating means therefor and then allowed to drop on to the bars 41 so as to jar the discharge electrodes by a vertical blow. The knocking means for the collecting electrodes are here shown as tilting levers 55 weighted at each end and carried by a rocking shaft 56 having an arm 57 whereby it may be operated by suitable means such as chain or otherwise. The knocker levers 50 extend directly over the respective collecting electrodes so that as said levers are thrown one way or the other by said operating means they will strike the said electrodes and impart a vertical blow thereto.

What I claim is:

1. In an apparatus for electrical precipitation of suspended particles from gases, the combination with an insulated support and a vertically extending discharge electrode mounted on said insulated support and extending downwardly therefrom, of hammer means mounted on said insulated support for applying a vertical blow to the upper end of said electrode.

2. In an apparatus for electrical precipitation of suspended particles from gases, a horizontal insulated frame, vertically extending discharge electrodes hung from said frame, and hammer means movably mounted on said insulated frame and adapted to jar the discharge electrodes so as to dislodge material deposited thereon, and operating means for said hammer means comprising an insulator for the purpose set forth.

3. In an apparatus for electrical precipitation of suspended particles from gases, the combination of insulated supporting means, discharge electrodes hung therefrom and hammer means mounted on said insulated

supporting means for jarring said discharge electrodes to dislodge deposited material therefrom.

4. In an apparatus for electrical precipitation of suspended particles from gases, the combination of insulated supporting means, discharge electrodes hung therefrom and means on said insulated supporting means

for imparting a vertical blow to said supporting means adjacent to said discharge electrodes to dislodge deposited material therefrom.

In testimony whereof I have hereunto subscribed my name this 1st day of September 1922.

WALTER A. SCHMIDT.
